UNITED STATES PATENT OFFICE.

WILHELM B. BRONANDER, OF BROOKLYN, NEW YORK, ASSIGNOR TO INTERNATIONAL CIGAR MACHINERY COMPANY, A CORPORATION OF NEW JERSEY.

CIGAR-BUNCH MANIPULATOR.

Application filed November 10, 1923. Serial No. 674,046.

To all whom it may concern:

Be it known that I, WILHELM B. BRONANDER, a citizen of the United States, residing at Brooklyn, county of Kings, and State of New York, have invented a new and useful Improvement in Cigar-Bunch Manipulators, of which the following is a specification.

This invention relates to an improvement in cigar bunch manipulators of the rotating 10 drum type.

Heretofore, manipulators of this type have included a concave member substantially concentric with the perimeter of the rotating drum and presenting an inflexible operating surface through the member as a whole has been yieldingly mounted. The main object of the present invention is the production of a device having a flexible manipulating member coacting with the rotating drum 20 in order to act upon the rotating cigar bunch in a more gentle manner and effect a more even distribution of the filler within the binder. With this and other objects not specifically mentioned in view, the invention 25 consists in certain combinations and constructions which will be hereinafter fully described and then specifically set forth in the claims hereunto appended.

In the accompanying drawings, which 30 form a part of this specification and in which like characters of reference indicate the same or like parts, Fig. 1 is a side elevation, partly in section, of a manipulator constructed in accordance with the invention; Fig. 2 is a detail view of a part of the device 35 shown in Fig. 1, showing the manner of mounting the flexible manipulating member; Fig. 3 is a sectional view taken on the line 3—3 in Fig. 1; and Fig. 4 is a perspective view of the flexible manipulating member.

In carrying the invention into effect, there is provided a rotating drum and a flexible manipulating member spaced from the perimeter of said drum, the spacing being sufficient to accommodate a cigar bunch so that it will be rolled between the drum and member under gentle pressure, and a support for the flexible member. In the best constructions, the drum and flexible member will be somewhat concaved transversely to manipulate the bunch ends preparatory to shaping them permanently in the mechanism, not shown, to which the bunch is transferred after it has been manipulated.

These various parts may be widely varied in construction within the scope of the claims, for the particular structure selected to illustrate the invention is but one of many possible concrete embodiments of the same. 60 The invention therefore is not to be restricted to the precise details of the structure shown and described.

Referring to the drawings, 5 indicates a rotating manipulating drum of a type well known in the art and therefore needing no detailed description. While this drum may have a cylindrical or a conical operating surface at its perimeter, dependent upon the contour of the cigar bunch to be manipulated; as shown, the perimeter of the drum is concaved at 6 to accommodate the particular form of cigar bunch shown in Fig. 3. 70

Coacting with the drum 5 is a flexible manipulating member 7 which also may be cylindrical or conical or transversely concaved, as the case may be, and also is or may be constructed of thin sheet metal. This flexible member is bent around a portion 75 of the perimeter of the drum 5, and its ends are secured to a suitable support. The mid-section of this flexible member lies nearer to the perimeter of the drum than its ends. Each of its ends is doubled back at 8 and provided with a slot 9, and a screw 10 passes 80 through this slot and is threaded into a support 11, the head of the screw clamping the end of the flexible member to the support. As clearly shown in Fig. 1, the support 11 is curved around a portion of the 90 perimeter of the drum 5 and it is provided with a slotted fork 12, the tines of which lie on either side of a boss 13 formed on a bracket 14 which supports the shaft 15 of the drum 5 before referred to. Mounted 95 in the boss 13 is a pin 16 extending through the slots of the fork 12 and held in position by means of a set screw 17. In each tine of the fork 12 is threaded an adjusting screw 18 bearing against the pin 16. The purpose 100 of the structure just described is to provide means whereby the support may be adjusted toward and away from the drum in accordance with the diameter of the bunches to be manipulated.

This structure, however, does not hold the support 11 rigidly in adjusted position, which would be undesirable since a slight tilting action of the support is necessary to obtain the best results. For the purpose 110

of permitting this slight tilting action, the support 11 bears against two springs 19, one on either side of the fork 12. These springs are housed in bosses 20 formed on the bracket 14 before referred to, and their tension is regulated by means of adjusting screws 21 of well known character and operation.

The device is used in connection with a suitable bunch forming mechanism which is, or may be, of the Chianti belt type indicated diagrammatically at 22 in Fig. 1. This bunch forming mechanism encloses filler in a binder and delivers it to a table 23, across which it is moved by means of a pusher 24, to the entrance of the passage between the drum 5 and flexible manipulating member 7, the bunch in several positions being indicated in Fig. 1 by the reference letter B, the arrows showing the direction of bunch travel. The table 23 and pusher 24 form a part of the bunch forming mechanism and lie outside the scope of the present invention; and since they are well known in the art, a detailed description of the same is omitted in the interest of brevity and clearness.

The distance between the perimeter of the drum 5 and the leading end of the flexible member 7 at the entrance of the passage before referred to, is somewhat less than the diameter of the cigar bunch; and when a bunch is pushed into the entrance of the passage, the spring 19 nearest said entrance yields a little, and the support 11 tilts on the pin 16. The spring 19 exerts a gentle pressure on the bunch radially with respect to the drum 5. As the bunch is rolled along through the passage, the flexible member 7 yields independently of the yielding of the spring 19 and becomes deformed or sprung out of its normal shape, thereby changing the direction of the applied pressure slightly. When the bunch reaches a point over the fork 12, the support comes back to its normal position and as the bunch moves farther along it is tilted slightly in the opposite direction, but the flexible member 7 exerts its independent pressure throughout the travel of the bunch through the passage. When the bunch reaches the upper end of the support and flexible member, it comes in contact with a yielding finger 25 of a bunch carrier, the purpose of which is to transport the manipulated

bunch to a shaping mechanism, not shown. The action of the rotating drum in rolling the bunch forward causes it to roll under the finger 25 into the bunch position shown at the right and top of Fig. 1, which is the position it occupies while being transported. The bunch carrier is operated by a rocking movement of a shaft 26 upon which it is mounted. This transporting mechanism is well known in the art and lies outside the present invention; a detailed description thereof is therefore omitted in the interest of brevity.

What is claimed is:

1. A cigar bunch manipulator comprising a rotating drum, a flexible manipulating member coacting therewith, and a support for said member.

2. A cigar bunch manipulator comprising a rotating drum, a flexible manipulating member coacting therewith, and a support for said member, said drum having an operating surface shaped in accordance with the contour of the bunch to be manipulated.

3. A cigar bunch manipulator comprising a rotating drum, a flexible manipulating member coacting therewith, and a support for said member, said member having an operating surface shaped in accordance with the contour of the bunch to be manipulated.

4. A cigar bunch manipulator comprising a rotating drum, a flexible manipulating member coacting therewith, and a support for said member, said drum and said member having correspondingly concaved operating surfaces.

5. A cigar bunch manipulator comprising a rotating drum, a flexible manipulating member coacting therewith, and a support for said member engaging its ends only.

6. A cigar bunch manipulator comprising a rotating drum, a flexible manipulating member coacting therewith, and a support for said member, said member being constructed of sheet metal.

7. A cigar bunch manipulator comprising a rotating drum, a flexible manipulating member coacting therewith, and a support for said member, said support being adjustable towards and away from the axis of said drum.

In testimony whereof, I have signed my name to this specification.

WILHELM B. BRONANDER.
